CLAIM

The ornamental design for a smart safe with exterior buttons, as shown and described.

DESCRIPTION

FIG. 1 is a perspective view of a smart safe with exterior buttons showing my new design.

FIG. 2 is a front view of the smart safe shown in FIG. 1.

FIG. 3 is a rear view of the smart safe shown in FIG. 1.

FIG. 4 is a left side view of the smart safe shown in FIG. 1.

FIG. 5 is a right side view of the smart safe shown in FIG. 1.

FIG. 6 is a top view of the smart safe shown in FIG. 1.

FIG. 7 is a bottom view of the smart safe shown in FIG. 1; and,

FIG. 8 is another perspective view of the smart safe shown in FIG. 1, with the lid shown in an open position.

The broken lines shown in the drawings represent portions of the smart safe with exterior buttons that form no part of the claimed design.

1 Claim, 7 Drawing Sheets
